(57) **CLAIM**

The ornamental design for a VR stand as shown and described.

DESCRIPTION

FIG. 1 is a front and left side perspective view of a VR stand, showing our new design.

FIG. 2 is a rear and right side perspective view of the VR stand shown in FIG. 1.

FIG. 3 is a front elevation view of the VR stand shown in FIG. 1.

FIG. 4 is a rear elevation view of the VR stand shown in FIG. 1.

FIG. 5 is a left side view of the VR stand shown in FIG. 1.

FIG. 6 is a right side view of the VR stand shown in FIG. 1.

FIG. 7 is a top plan view of the VR stand shown in FIG. 1.

FIG. 8 is a bottom plan view of the VR stand shown in FIG. 1; and,

FIG. 9 is a front and left side perspective view thereof. The broken lines depict portions of the VR stand that form no part of the claimed design. The unclaimed sliding support plate in FIGS. 1 and 9 is shown in alternate positions.

1 Claim, 9 Drawing Sheets
